UNITED STATES PATENT OFFICE.

WILLIAM H. MILLER, OF CINCINNATI, OHIO, ASSIGNOR TO THE MILLER CALK COMPANY, OF SAME PLACE.

DETACHABLE CALK FOR HORSESHOES.

SPECIFICATION forming part of Letters Patent No. 341,038, dated May 4, 1886.

Application filed January 12, 1885. Serial No. 152,561. (No model.)

To all whom it may concern:

Be it known that I, WILLIAM H. MILLER, of Cincinnati, Hamilton county, Ohio, have invented a new and useful Removable Calk for Horseshoes, of which the following is a specification.

My invention relates to an improved form of removable calk or sharpening attachment for horseshoes, as hereinafter particularly described.

In the accompanying drawings, Figure 1 is an under side perspective view of a sharpening attachment embodying my invention, said attachment being shown in place upon the horseshoe. Fig. 2 is an upper, and Fig. 3 an under, side view of the members of my attachment separated from each other and from the shoe. Fig. 4 is a transverse section of such attachment in place upon the shoe.

20 A may represent a horse's hoof, and B a customary horseshoe.

It is well known that in order to insure contact exclusively at and near the outer wall of the hoof it is the practice to chamfer both the hoof-sole and the top of the shoe, so as to leave an interstice. I avail myself of this interstice to receive the points *c* of hooks or lugs *C*, that project at first upward and then outward from the tops of two similar curved plates, *D D'*, from whose lower surfaces or soles project two portions, *E E'*, of a supplementary toe, *e e'*, and two supplementary heels, *F F'*, all of which projections have sharp edges, as shown. One of these plates, *D*, has near its mid-length a square or other non-circular socket, *G*, and the other plate, *D'*, has a circular socket, *G'*, for the corresponding head, *H*, and point *H'* of an expanding screw-bolt, *I*, which carries a nut, *J*. The said plates having been engaged 40 with their hooks *C*, interposed between the hoof and the shoe at the inner or concave edge of the latter, and the bolt *I* having been inserted in the sockets *G G'*, screwing of the nut *J* outward operates to press the said plates asunder, and to cause their said hooks to firmly engage behind the shoe, as shown in Figs. 1 and 4, in which condition the calk or supplementary shoe becomes for the time being an adjunct of the shoe proper.

50 My improved calk may be composed of any suitable material—such as steel or wrought or malleable iron—and is preferably plated with tin, for the double purpose of preventing rust and affording a surface to which snow and ice

will not adhere, which otherwise would be liable to ball the animal's foot.

I am aware that supplemental horseshoes consisting of two parts hinged together at their forward ends and having expanding-screws at their rear ends are old, and such I do not claim.

I am also aware that supplemental horseshoes have been formed of two separate pieces of metal held upon the shoe proper by means of an expanding screw placed at their mid-length, and do not claim this, broadly, as my invention. In this device the two pieces which form the supplemental shoe are bowed inward or toward the center of the foot, and only bear upon the shoe at their extremities. This is objectionable, for the reason that should a stone come against this inturned portion it would most certainly wrench the whole shoe and foot very severely, thereby not only endangering the breaking or displacement of the supplemental shoe, but also the loosening of the shoe proper.

I am also aware that a supplemental shoe has been formed in two sections conterminous with the main shoe, articulated at their foremost extremities, and provided with an expanding-bolt for holding them in place.

I claim herein as new and of my invention—

1. The calk or supplementary horseshoe consisting of the separate plates *D D'*, conterminous with and bearing throughout their length upon the under surface of the shoe proper, having the lugs *C*, the toes *e e'*, the heels *F F'*, and the sockets *G G'*, in combination with the nutted bolt or expander *H H' I J*, located at or near the mid-length of the shoe, as and for the purpose designated.

2. The calk or supplementary horseshoe consisting of the separate plates *D D'*, conterminous with and bearing throughout their length upon the shoe proper, having the upwardly and outwardly projecting lugs *C c C c*, with the sockets *G G'*, formed in said lugs above the plane of the plates *D*, the toe-pieces *e e'*, and the heel-pieces *F F'*, in combination with the expander *H I J*, located at or near the mid-length of the shoe and above the plane of the plates *D D'*, as set forth.

In testimony of which invention I hereunto set my hand.

Attest: WILLIAM H. MILLER.
